UNITED STATES PATENT OFFICE.

MICHAEL J. GREEN, OF ROCKFORD, ILLINOIS, ASSIGNOR TO ECLIPSE GAS STOVE COMPANY, OF ROCKFORD, ILLINOIS, A CORPORATION OF ILLINOIS.

GAS HEATING APPLIANCE.

1,074,789.

Specification of Letters Patent. Patented Oct. 7, 1913.

Application filed February 11, 1913. Serial No. 747,637.

To all whom it may concern:

Be it known that I, MICHAEL J. GREEN, a citizen of the United States, residing at Rockford, in the county of Winnebago and State of Illinois, have invented certain new and useful Improvements in Gas Heating Appliances, of which the following is a specification.

The object of this invention is to construct the burners of a gas stove of a simple construction and few parts, and whereby the burners may be removed from the stove without the appliance of tools or of removing bolts or screws, in order that the burners may be cleaned.

The further object is in the formation and location of the several parts, that is, the gas-manifold, valves and detachable burners so that the same are thoroughly accessible to repair and adjustment.

The further object is to furnish with a burner of this type, a pilot light to light the main burners.

In the accompanying drawings, Figure 1 is an end elevation of a gas stove showing my improved burners applied thereto, a portion of one of the burners being broken away. Fig. 2 is a face view of the portion of the stove containing the burners. Fig. 3 is a vertical section through one of the burners on the line 3—3 of Fig. 1. Fig. 4 is an enlarged detail of the gas and air inlet at the lower end of the burner flue. Fig. 5 is a plan view of the burners taken with the cover or top of the stove removed. Fig. 6 is an enlarged sectional detail view of a burner head taken on the line 6—6 of Fig. 3.

The burners and gas manifold may be applied to any form of gas heating stove, having here shown them as applied to the end of a stove formed with the end wall 7 and the heating compartment 8 positioned just below the top plate 9 of the stove. The gas-intake manifold 10 has the brackets 11 formed integral therewith bolted to the end wall 7. A pilot header 12 in the form of a pipe located within the heating compartment 8, lying parallel with the gas manifold and formed with a plurality of jets 13 therein, has a pipe connection 14 communicating with the central portion thereof, and which pipe connection extends to the front of the stove having a common type of air intake valve 15 connected therewith. The opening 31 in the front of the stove allows a match

to be inserted to light the pilot lighter. The gas manifold 10 has connection with said valve 15 by the pipe connection 16 there being a stop cock 17 located on the connection 16 to control the supply of gas going to the pilot burner. In this construction of stove there are four burners and each burner receives gas independently from the gas-manifold. As each burner is of a similar construction I will describe in detail the construction and operation of but one of the burners nearest the front of the stove, which description will of course apply to all the burners. The plate 18, a portion of the stove structure, secured to the end wall 7 has openings 19 therein through which the burner heads are inserted. The burner body is formed of a vertical flue pipe 20, circular at the top, and formed with a recess in its underside having at one side thereof a stud 21, which when the burner is placed with the recess in connection with plate 18, holds the burner in position, and secured by bolts 22 to the burner body is the burner head 23 whose sides converge to an opening 24, there being a screening 25 interposed between the burner head and body. The lower end 27 of the burner flue is enlarged to form a suitable air-intake.

A common form of adjustable needle valve 26 for admitting gas to the burner flue is located at the air-intake of the flue and receives its supply of gas through the pipe connection 28 which communicates with the gas-manifold 10, there being a stop cock 29 located on said connection to regulate the supply of gas from the gas-manifold to the burner, said stop cock being operated by the handle 30 at the front of the stove. The stop cocks 29 of the several connections are positioned at various distances from the gas-manifold, as it is seen in Fig. 1, in order that their handle controls at the front of the stove may be operated without conflicting.

The operation of the burners is as follows:—With a supply of gas to the gas-manifold, the stop cock 17 is opened, thereby allowing gas to pass to the pilot head charged with air from the air intake 15, and the gas issuing from jets 13 may be lighted by inserting a lighted match through opening 31 adjacent the pilot, thus giving a plurality of pilot lights throughout the length of the header 12. Gas is then admitted to the burners by turning handles 30 of the

several burners which open the stop-cocks 29 allowing the gas to pass from the gas-manifold through connections 28 and escape through the needle valves 26, at which points 5 the charges are mixed with air and pass through the flues 20, being discharged at burner head openings 24 and ignited by the pilot flames.

When in use it is often desired to operate 10 the stove at short intervals of time and not to keep the main burners lighted continuously, resulting in the waste of gas. Thus I provide the pilot header extending adjacent the 15 openings of all the burner heads to ignite same when desired, and it will be seen that by the use of the individual burners with independent gas controls, that the heating capacity can be limited according to the amount of heat required, that is, by using 20 only the required number of burners. Furthermore, because of the novel construction and arrangement of the manifold and burners, each burner can be removed bodily without removing any parts or requiring the use 25 of tools by simply lifting the burner from its engagement with the plate 18 and withdrawing the burner head through the opening 19 in said plate. The burners can be easily cleaned then and also with the burners 30 removed, the gas connections and manifold are left thoroughly accessible.

I claim as my invention—

1. The combination of a stove and a gas heating appliance comprising, a gas manifold, a plate at one side of the heating 35 compartment of the stove, said plate formed with openings therein, gas burners, each burner having a flue and discharge head, the discharge head extending through one of said openings in said plate, the burner being supported by said plate, and a gas passage 40 for each burner communicating with the manifold and discharging in said flue.

2. The combination of a stove and a gas 45 heating appliance comprising, a gas manifold, a side member of the heating compartment of the stove formed with openings therein, gas burners, each burner having a flue and discharge head, the discharge head 50 extending through one of said openings, the burner resting on said side member and having a stud for contacting the side member and holding the burner in position, and a gas passage 55 for each burner communicating with the manifold and discharging in said flue.

3. The combination of a stove and a gas 60 heating appliance comprising, a gas-manifold, a side member of the heating compartment of the stove formed with openings 65 therein, gas burners, each burner having a flue, a discharge head and an air intake portion at the end of the flue opposite said discharge head end, the discharge head extending through one of said openings, a gas

passage for each burner communicating with the manifold and discharging into said flue at the air intake portion thereof, and a loose connection between the burners and said side member, adjacent the discharge 70 head and from which the burners are detachable.

4. The combination of a stove and a gas heating appliance comprising, a gas supply pipe, a side member of the heating compartment of the stove having an opening therein, a gas burner having a flue and discharge head, the discharge head extending through said opening, the burner adapted to rest on said side member and having a 80 stud for contacting the side member and holding the burner in position, a gas passage communicating with the gas supply pipe and discharging in said flue, and a valve for controlling the supply of gas to the burner. 85

5. The combination of a stove and a gas heating appliance comprising, a gas supply pipe, a side member of the heating compartment of the stove having an opening therein, a gas burner having a flue, a discharge 90 head and an air intake portion at the end of the flue opposite the discharge head, said head extending through the opening in the said member, a gas passage communicating with the gas supply pipe and discharging 95 into the flue at the air intake portion thereof, a valve controlling the supply of gas to said burner, and the burner being supported by the side member and detachable therefrom. 100

6. The combination of a stove and a gas heating appliance comprising, a gas manifold fixedly secured to the side of the stove, gas burners, each having a flue and discharge head, the burners arranged vertically 105 at the side of the stove to the outside of the manifold and having the discharge heads communicating with the heating compartment of the stove, a gas passage for each burner leading from the manifold to the 110 lower end of each flue and discharging therein, a valve located in each passage for controlling the supply of gas to a burner, and a support for each burner whereby the burners may be lifted therefrom without 115 deranging any of the other said elements.

7. The combination of a stove and a gas heating appliance comprising, a gas manifold fixedly secured to the side of the stove, gas burners, each having a flue and discharge head, the burners arranged vertically 120 at the side of the stove, to the outside of the manifold and having the discharge heads communicating with the heating compartment of the stove, a gas pipe connection for 125 each burner carried by the manifold and discharging into the flue at the lower end thereof, a valve for each connection having an operating handle operably located at the front of the stove, and a support for 130

each burner whereby the burners may be lifted therefrom without deranging any of the heating appliances.

8. The combination of a stove and a gas heating appliance comprising, a gas manifold, a plurality of burners each having a flue and discharge head, the burners spaced in substantially vertical positions at the side of the stove, a gas passage for each burner communicating with the manifold and burner flue, a valve located on each of said passages and positioned at varying distances from said gas-manifold, a rod for each valve having connection therewith, extending substantially horizontal in vertical alinement, to the face of the stove, and an operating handle for each rod at the face of the stove.

9. The combination of a stove and a gas heating appliance comprising, a gas-manifold, a plurality of burners each having a flue and discharge head, the burners spaced in substantially vertical positions at the side of the stove, a gas passage for each burner communicating with the manifold and burner flue, a valve located on each of said passages and positioned at varying distances from the gas-manifold, a rod for each valve having connection therewith and extending to the face of the stove, certain gas passages being offset to one side of said rod, and an operating handle for each rod at the face of the stove.

10. The combination of a stove and a gas heating appliance comprising, a gas-manifold positioned parallel to the side of the stove, a plurality of burners each having a flue and discharge head, the flues being located at the outside of said manifold, a gas passage for each burner communicating with the manifold and burner flue, a valve for each passage, the valves located at receding distances from the manifold and in vertical alinement, a rod connected to each valve and extending parallel with said manifold to the face of the stove, and an operating handle for each rod at the face of the stove.

11. The combination of a stove and a gas heating appliance comprising, a gas-manifold located adjacent the side of the stove, a plurality of burners each having a flue and discharge head, the flues located to the outside of the manifold, a gas passage for each burner communicating with the manifold and burner flue, a valve located on each passage, the valves at varying distances from the manifold, a horizontal rod for each valve extending to the face of the stove in vertical alinement, and an operating handle at the face of the stove for each valve, the handles being arranged at varying distances from the face of the stove to allow non-conflict of the operation of said handles.

12. The combination of a stove and a gas

heating appliance comprising, a gas-manifold positioned at one side of a stove, a plurality of gas-burners positioned vertically disposed at said side of a stove, a gas-passage for each burner, disposed intermediate the burners and said side of a stove and communicating with the manifold, a valve for each gas-passage, control means for the valves, and supporting means for the burners to allow the burners to be lifted from their said position without deranging any of the other said elements.

13. The combination of a stove and a gas heating appliance comprising, a plurality of burners and valves therefor, controls for the valves, the controls extending to the face of the stove, substantially in alinement in a given plane, and each having at their operating end an operating handle of an operating length greater than the distance between the said controls, said handles being located at graduated distances from the face of the stove.

14. The combination of a stove and a gas heating appliance comprising, a gas-manifold located at the outside of a stove, a plurality of gas-passages extending downward from the manifold and having discharge ends disposed below said gas-manifold, a valve located in each gas-passage and a control therefor, and a gas-burner for each gas-passage, communicating with a discharge end and extending upward and entering the stove above said gas-manifold.

15. The combination of a stove and a gas heating appliance comprising, a plurality of burners and valves therefor, a control for each valve extending to the face of the stove, each control having an operating handle, said controls being spaced apart a distance less than the operating length of said handles, and the handles being arranged at graduated distances from the face of the stove.

16. The combination of a stove and a gas heating appliance comprising, a gas-manifold, a plurality of gas-burners, a gas-passage for each burner communicating with the gas-manifold and certain of the gas-passages having offset portions, a valve in each gas-passage on a non-offset portion, the valves located at varying distances from the gas-manifold, and a control for each valve, the controls leading from the valves in a common direction, and certain of said controls passing through the space provided by the offsetting of said certain gas-passages.

17. The combination of a stove and a gas heating appliance comprising, a gas manifold, a plurality of gas-passages leading from the gas-manifold substantially in alinement and certain of the gas-passages having offset portions, at varying distances from the gas-manifold, a valve in each gas-

passage located on a non-offset portion, and a control for each valve, the controls leading horizontally from the valves in a common direction and to the face of the stove, and 5 certain of said controls passing through the space provided by the offsetting of said certain gas-passages.

In testimony whereof I have hereunto set my hand in presence of two subscribing witnesses.
